(57) **CLAIM**

The ornamental design for heat-dissipation fan housing, as shown in the accompanying drawings.

DESCRIPTION

FIG. 1 is a perspective view of the heat-dissipation fan housing in accordance with the embodiment of the claimed design;

FIG. 2 is a right side elevational view thereof;

FIG. 3 is a top plan view thereof;

FIG. 4 is a front elevational view thereof;

FIG. 5 is a bottom plan view thereof;

FIG. 6 is a left side elevational view thereof;

FIG. 7 is a rear elevational view thereof; and

FIG. 8 is a partially cut-away perspective view thereof, taken from an angle rotated 90° relative to the angle of FIG. 1; and,

FIG. 9 is a partially cut-away perspective view thereof, taken from an angle rotated 270° from the angle of FIG. 1.
